UNITED STATES PATENT OFFICE.

JOHN R. THOMAS, OF CINCINNATI, OHIO, ASSIGNOR TO J. A. FAY & EGAN COMPANY, OF CINCINNATI, OHIO, A CORPORATION OF WEST VIRGINIA.

PLANING-MACHINE.

SPECIFICATION forming part of Letters Patent No. 686,428, dated November 12, 1901.

Application filed March 5, 1900. Serial No. 7,296. (No model.)

To all whom it may concern:

Be it known that I, JOHN R. THOMAS, a citizen of the United States, residing at Cincinnati, in the county of Hamilton and State of 5 Ohio, have invented certain new and useful Improvements in Planing-Machines, of which the following is a specification.

It is the object of my invention to provide a planing-machine adapted to act on the stock 10 during the passage of the same through the machine by means of rotary cutters and stationary cutters in such manner that a highly-surfaced product may be obtained.

My invention consists in providing in a machine of the character described a pair of horizontally-disposed rotary cutter-heads adapted to reduce the stock to a thickness and a stationary or fixed knife planing device for providing the stock with a highly-finished 15 surface, to which the stock is fed after being operated upon by the pair of horizontally-disposed cutter-heads; further, in supplementing the above arrangement by a pair of vertically-disposed cutter-heads for planing 20 or tonguing and grooving the edges of the stock with a stationary or fixed knife cutting device to either side of the stock operating upon the stock after leaving the vertically-disposed rotary cutter-heads. The object of this 25 arrangement of cutters is to first reduce the stock to thickness or to a width by means of rotating cutter-heads.

In rotating cutter-heads the stock is reduced by means of knives attached to a plurality-sided cutter-head, the cutter-head revolving at a high rate of speed with each knife as it passes the stock, scooping out a portion thereof taking the form of a chip; but the action of the cutter is always in the 35 circle in which it swings, and each successive cutter takes out an additional chip as the cutter-head swings and the feeding-rolls of the machine advance the stock; but each time a cutter cuts it is always on the circle of the 40 circle in which it swings, and by the time the next succeeding cutter will have swung sufficiently to reach the stock the stock will also have advanced, and the cutter then cutting on the circle of its swing leaves a slight ridge between 45 its cut and the cut of the cutter in advance of it. In practice the cutter-heads are rotated 50

at a high rate of speed, and each cutter-head is usually provided with two or more cutters. The feed of the stock through the machine is also more or less rapid, in practice ranging all 55 the way from eighteen to about forty feet per minute to produce comparatively good stock in hard wood. The greater the speed of feed the farther the stock will advance through the machine between the cut of each successive cutter on the cutter-head and the more perceptible will be the ridge left between each two cuts, depending on the ratio of feed. There is a limit to the speed at which a cutter-head can be successfully rotated in practice, and consequently a limit to the rate of feed through a machine employing rotary cutter-heads to provide the stock with an apparently smooth surface, each successive cut, however, being always perceptible in the product, showing the more plainly the greater the rate of feed is in ratio to the speed of the cutter-head. The ridges left by the cutters when a slow feed is used are sometimes not perceptible unless the stock is held near the plane of 60 the eye, so that the light may shine upon the stock and the eye glance along its surface, or it may not appear until the stock is subjected to subsequent treatment—varnishing, for instance—but is always present and an objection. In order to avoid these objections, therefore, and to provide a machine capable of producing a perfectly plane smooth surface at a greatly-increased rate of feed, I supplement 65 the horizontal rotary cutters with stationary or fixed knife planing devices acting upon the stock after the rotary cutters have reduced the stock to thickness and adapted to take a thin shaving off of the face side of the stock, thereby providing the stock with a perfectly 70 plane smooth face free of ridges and enabling the stock to be passed through the machine at a greatly-increased rate of feed, while producing a better product. I prefer to mount the horizontal stationary or fixed knives in a 75 box, which may be inserted into the machine, and prefer to make the position of this box the point with reference to which all other agencies of the machine are adjusted.

My invention consists, therefore, further, in 80 providing a feeding-in table in advance of the lower cutter-head, adjustable to raise and 85

lower with reference to horizontal plane of the line of cut of the latter and having an adjustable nose adapted to be adjusted toward and from the cutter-head.

5 My invention relates, further, to the pressure devices above the horizontal or fixed knives; and it consists in providing a pressure device in which friction shall be minimized and having a substantially continuous bearing for the 10 stock transversely of the machine extending diagonally of the frame above the fixed cutters.

15 My invention consists, further, in providing a machine having a pair of rotary cutter-heads, cutting first for reducing the stock to a thickness, and arranged to then direct the stock against a series of rigidly-positioned supporting and guiding agencies, both above and below and to one side, forming a die for the 20 stock, and while passing therethrough subjecting it to the action of fixed knife cutting agencies.

25 My invention consists, further, in the parts and in the construction, arrangement, and combinations of parts hereinafter more fully described and claimed.

30 In the drawings, Figure 1 represents a plan view of my improved device with the ends of the frame broken away, with the upper cutter-head also broken away for better illustration. Fig. 2 is a side elevation of my improved device. Fig. 3 is a central longitudinal section of the lower cutter-head and saddle broken away at the middle. Fig. 4 is a detail in cross-section on the line *z z* of Fig. 3. Fig. 5 is a detail in cross-section on the line *v v* of Fig. 35 3. Fig. 6 is a detail in side elevation representing the adjustable feeding-in table before the cut of the lower cutter-head. Fig. 7 is a detail in cross-section on the line *w w* of Fig. 40 6. Fig. 8 is a cross-section of the pressure device for the horizontal fixed knives on the line *x x* of Fig. 2, showing the roll-sections and knife-box in side elevation. Fig. 9 is a 45 central horizontal cross-section of the roll-sections, boxes, and shaft. Fig. 10 is a detail in section on the line *u u* of Fig. 8. Fig. 11 is a side elevation of the side-cutting agencies and pressure device therefor, taken from the 50 middle of the machine. Fig. 12 is a detail in section on the line *y y* of Fig. 11.

55 *A* represents the frame of the machine, into or through which the stock is driven by suitable feeding devices, as by means of feeding-rolls *B B' B² B³*, driven in any suitable manner from a suitable source of power. At the feeding-in end of the machine I prefer to mount an upper horizontal cutter-head *C* and a lower horizontal cutter-head *C'*. The cutter-head *C* is rotatively mounted in bearings 1 of a housing 2, adjustable up and down on uprights 3 by means of screw-shafts 4, one at each side of the machine, which may be interconnected by a shaft 5 and gears 6 and 7. 60 The upper cutter-head may be held in rigid relation with the uprights by means of *T*-bolts and nuts 8, connecting the upright and hous- 65

ing. A chip-breaker 9 is provided in advance of the cutter-head and a pressure-bar 10 after the cutter-head. The lower cutter-head is 70 supported by a saddle 11, provided with sides 12, adjustable in ways 13 in the frame up and down, by means of set-bolts 14, adapted to be held in place by means of jam-nuts 15. The saddle 11 has ways 16, in which a cutter-head yoke 17 may slide longitudinally. The yoke carries bearings 18 for the cutter-head. It has a screw 19, which takes through a threaded aperture 20 in the saddle and has a bearing 21 in the yoke, by means of which the 80 yoke is given longitudinal movement with relation to the saddle. The yoke also carries a handle or grip 22, by means of which the yoke may be pulled longitudinally with relation to the saddle and through an opening 23 85 in the side of the frame. The saddle carries a bearing 24, in which I journal one member 25 of a clutch 26. This bearing may be on a bracket 24' of the saddle extending outwardly from the frame to allow for passage of the 90 belt operating the cutter-head. The other member of the clutch 27 is carried by the shaft 28 of the cutter-head. The clutch may take the form of a cone-and-cup clutch, the member 25 being the cup and the member 27 95 the cone. They may be interconnected by projections or dogs 29, preferably tapering to form more intimate union between the same. When the screw 19 is turned to force the cutter-head yoke inwardly, the members of the clutch make intimate contact, whereby the cutter-head shaft, with the cup-shaft 30 in the bearing 24, will form a rigidly-connecting shaft having three bearings, with the pulley 31 for driving the cutter-head, which is 100 preferably formed by the outer periphery of the cup located between two bearings in close 105 relation with each other to afford smoothness of operation and at the same time allow a removal of the cutter-head for the purpose of 110 sharpening and readjusting the cutters without removing the driving-belt for the same from its pulley, but allowing its pulley and driving-belt to remain in position. The screw 19 may extend a substantial distance into the 115 frame or only slightly, as may be desired. A clamp 32, which takes through a slot 33 in the saddle side, may hold the saddle rigid 120 with relation to the frame after adjustment. A pressure-bar 34 after the cut of the lower 120 cutter-head may be provided. A pressure plate or roll 35 takes above the lower cutter-head for holding the stock to its work. It may be given vertical adjustment on a standard 36 by means of a hand-wheel 37 and suitable adjusting-screws, shafts, and gears, and the standard may be arranged to swing upwardly out of the way to expose the cutter-head.

125 In advance of the lower cutter-head I provide an adjustable table 51. The table may have lugs 52, sliding in ways 53. The ways may be arranged in the frame or in a casting 54, bolted to the frame by means of bolts 48,

passing through slots 49 in flanges on the castings. Each casting can be adjusted longitudinally of the frame by reason of the bolt passing through a slot to line up the table—
 5 i. e., cause the inclined ways to have the proper relation toward each other for this purpose. A plate 55 is adapted to be bolted above the lug on the table after the latter has been seated on the way, so as to give it rigidity, both up and down and sidewise. The raising and lowering of the table may be effected by an adjusting-screw 56, screwing into an internally-threaded lug 57 under the table, with a gear 58 at the end of the adjusting-screw connecting with a gear 59 on the shaft 60, the latter having a hand-wheel 61 for turning it. The ways 53 are preferably inclined, so as to raise and lower the plane of the table and at the same time bring it toward and from the place of cut of the cutter-head. It has a toe-plate 62, separately adjustable to and from the vertical plane of the cutter-head, as by means of bolts 63 taking through slots 64 in the toe and into the table for fastening the toe in adjusted position with relation to the cutter-head, thereby bringing the edge of the table close to the cut of the cutter-head.

In my improved device the stock is preferably reduced to thickness by the upper cutter-head, the feeding-in table acting as a support for the stock while being operated upon by the upper cutter-head, with the feeding-in table adjustable to vary the depth of cut taken by the lower cutter-head. The stock after it has been operated upon by both of these cutter-heads is reduced to a thickness, with each side thereof a substantially plane surface, so that when it reaches the fixed knives, hereinafter described, the pressure agency above the fixed knives may exert a uniform pressure on the stock, so as to prevent marking of the stock by the fixed knives, and a tendency to gouge by the fixed knives, and to consequently produce stock with a superior surface and which after it leaves the machine has a uniform and even thickness throughout. After it has been so reduced to a substantially plane surface the stock is ready for operation by the succeeding cutting agencies following in the machine.

Immediately after the lower cutter-head I provide stationary or fixed knife cutting devices, which I prefer to mount in a detachable cutter-box 71, readily removable from the machine. The cutter-box 71 is supported in ways 72, rigid with relation to the frame, as on cross-girders 73. The cutting agencies for the fixed knife cutting devices are preferably sharp beveled-edge knives 70, secured in the cutter-box diagonally of the frame and direction of feed of the stock and also diagonally to a vertical plane. The cutting edge of the knife is stationarily presented to the stock as it advances, the knives being secured in the box in suitable manner, as by means of bolts taking through slots in the

knives to permit of adjustment of the latter in the cutter-box, with a shield or strengthening-plate for the knives interposed between the latter and the bolt-heads. Suitable pressure agencies are arranged above the fixed knives for holding the stock to the latter. The frame, at each side thereof, is provided with a standard 81, which may be connected so as to form a yoke. A pressure-device frame 82 is adjustable up and down in the yoke to and from the fixed knives, as by means of a screw-shaft 83 at each side of the yoke, collared with reference to the yoke and screwing into an internally-threaded lug 84 on the pressure-device frame. The screw-shafts support gears 85, meshing with gears 86 on a horizontal shaft 87, which may also carry a hand-wheel 88 for turning the same. One or more transverse shafts or rods 91, extending diagonally of the frame and of the direction of feed, may be supported by the pressure-device frame, preferably one for each fixed knife. This shaft or rod is preferably non-rotatable and has taking thereabout a plurality of sleeves 92, having diagonal bores to take about the shaft, with a spline 93 interposed between the rod and sleeves to make the two relatively stationary. The sleeves are provided with externally-journal faces extending at right angles to the length of the machine and to the direction of the feed. Each of the sleeves when mounted on the shaft preferably contacts or makes substantial contact with its neighbor, so as to form a substantially continuous transverse but advancingly-stepped journal for the roll-sections hereinafter described.

A series of roll-sections 94 are provided. They are preferably in the form of rings, having inner bearing-faces taking over the journal-faces, with their peripheries arranged to make contact with the stock and extending at right angles to the length of the machine and to the direction of feed of the stock and forming a substantially continuous bearing upon the stock transversely of the machine and extending diagonally across the same above the cutting edges of the stationary or fixed knife. In a machine of this character the stock is fed through the machine at a very high rate of speed, and the stationary or fixed knives are arranged diagonally across the same, so as to take a shear cut off the stock. It is necessary in order to do smooth work that substantial pressure be exerted on the stock, so that the stock may be forced against the cutters firmly, so that it may not rise whenever hard or knotty places in the stock are being cut. I have also found it desirable to have a substantially continuous pressure exerted transversely of the machine above the diagonally-arranged fixed knives, so that there may be no points transversely of the machine where no pressure is exerted. Any substantial space left between the sections of the rolls would be noticeable on the stock. I provide each end of the transverse rods

91 with a box 95, taking into ways 96 in the pressure-device frame and preferably having a longitudinal bore with an inner diagonal face 97, against which the inner face of the 5 end sleeve and roll-section may take. It has an outer end 95' square with itself, but diagonal to the end of its supporting-frame 82, the way 96 having a corresponding end. The spline 93 may be continued through the box 10 95, so as to make the boxes, rod, and sleeves relatively stationary. A spring 98 or other suitable yielding pressure device may be provided for yieldingly holding the pressure-rolls in normal position. They may be interposed between the roll-boxes 95 and a 15 yoke 99. Set-bolts 100 may regulate the tension of the springs, and jam-nuts hold the set-bolts in adjusted position, with washers interposed between the bolts and springs. The 20 spring or yielding pressure agency may be dispensed with, the set-bolts taking direct against the boxes, making a pressure device rigid with relation to the knives and frame. When thus constructed, my improved device presents 25 a fixed and unyielding upper line of contact-faces, by which the stock is guided after it leaves the rotary horizontal cutter-heads, which reduce it to a thickness, with the lower line of guiding-faces and the side gage for 30 the stock also rigid, forming, in effect, a die through which the stock is forced by the feeding agencies, determining the line of cut with great accuracy and producing an exceptionally smooth product. The rotating cutter-head will leave slight ridges or marks by the 35 knives, being the more perceptible the faster the rate of feed of the stock, all of which are removed by the fixed knives and the stock left perfectly smooth and plane, enabling a 40 much higher rate of feed of stock to be maintained, with a greater perfection in product, than in the old constructions, in which rotary cutter-heads only are employed, the increase in speed of feed being from one hundred to 45 three hundred per cent. or more, and the stock being first reduced to a thickness by rotary cutter-heads cutting at top and bottom of same and the machine being provided with an adjustable feeding-in table before the lower 50 cutter-head the stock is reduced to an even thickness throughout, insuring an even pressure above the fixed knives and producing superiority in product.

The stock is next preferably operated upon 55 by a pair of vertically-disposed cutter-heads 101, mounted on spindles 102, journaled in bearings 103, and operated by pulleys 104. They may also be provided with chip-breakers and are given transverse adjustment by 60 means of adjusting-screws 106 in any ordinary way. These vertically-disposed rotary cutter-heads are for the purpose of preparing the stock for fixed knife devices 111, operating from right and left, which perform their 65 cutting operation after the vertical rotary cutter-heads. The rotary cutter-heads reduce the stock to substantially correct width, with

the fixed knife devices operating on the board thereafter to provide the edges of the board with a perfectly smooth surface. The upright fixed knives are secured at each side of the machine in a slide 116, in which a knife-box 117 may be inserted. The knife-box may be omitted, and the fixed knife may be fastened direct to the slide. An adjusting-screw 75 118 is provided for each slide for adjusting it transversely of the machine. The knife-box is secured in the slide by means of a pin 119, taking into a hole 120, formed partly in the slide and partly in the knife-box. The pin 80 has a flat side 121. When this flat side is coincident with the knife-box side, the knife-box may be removed, and when it is returned the pin is turned by means of handle 122. The manner of securing the fixed knife-blades 85 is by having a bolt 123 take through a slot 124 in the blade into an inclined part 125. A reinforcing-plate may be interposed between the bolt-heads and the blade in the knife-box 71 where long knives are used. A transverse shaft or bar 126 preferably spans the machine ahead of the vertical cutter-spindles, as by being mounted in lugs 127. The bar 126 has an arm or arms 129 projecting therefrom, with the arm sleeved about the shaft 95 90 by means of a sleeve 130 and arranged to swing about or with the bar. At its other end the arm is provided with seat 131, at which it is connected with the slide 116, as by means of having a pivoted bolt 132 taking into a slot 100 in the arm, with a nut 134 for fastening the arm and slide together. A pressure-bar 137 is sustained by the arm and is adapted to take against the stock, respectively, between the vertical spindled cutter-heads and the 105 vertically-disposed fixed knife devices. I prefer to make the connection between the pressure-bar and the arm by means of an extension 138 on the bar, slidale in ways 139 in the arm and adjustable therein by means of a screw-shaft 140, taking into an internally-threaded aperture or lug 141 on the arm, the screw-shaft being shouldered on the extension.

Any desired number of feeding-rolls may be employed, and they may, if desired, be all 115 placed at the feeding-in end of the machine.

It is obvious that changes may be made in the constructions I have preferred to show without departing from the spirit of my invention.

I claim—

1. In a planing-machine, the combination of upper and lower horizontally-disposed rotary cutter-heads cutting in advance to reduce the stock to a uniform thickness, with 125 one of the horizontally-disposed rotary cutter-heads cutting in advance of the other, with a horizontally-disposed stationary-knife cutting device cutting thereafter, substantially as described.

2. In a planing-machine, the combination of upper and lower horizontally-disposed rotary cutter-heads cutting in advance to reduce the stock to a uniform thickness and

- surface, with a horizontally-disposed stationary-knife cutting device cutting thereafter, with vertically-disposed rotary cutter-heads for the edges of the stock and vertically-disposed stationary-knife cutting devices arranged to operate upon the stock in the order named, substantially as described.
3. In a planing-machine, the combination of upper and lower horizontally-disposed rotary cutter-heads cutting in advance to reduce the stock to a uniform thickness, with one of the horizontally-disposed rotary cutter-heads cutting in advance of the other, with a horizontally-disposed fixed-knife cutting device cutting thereafter and a horizontally-positioned substantially continuous rotatable pressure agency opposite thereto, substantially as described.
4. In a planing-machine, the combination of an upper rotary cutter-head cutting first, a lower rotary cutter-head cutting next, with a feeding-in table below the upper cutter-head and in advance of the lower cutter-head, with means for raising and lowering the same, and horizontally-disposed stationary-knife cutting devices cutting after the lower rotary cutter-head, and a pressure device therefor, substantially as described.
5. In a planing-machine, the combination of an upper rotary cutter-head cutting first, a lower rotary cutter-head cutting next, with a feeding-in table below the upper cutter-head and in advance of the lower cutter-head, with means for raising and lowering the same, with an independent toe for the feeding-in table adjustable on the feeding-in table to and from the lower cutter-head, and horizontally-disposed stationary-knife cutting devices cutting after the lower rotary cutter-head, and a pressure device therefor, substantially as described.
6. In a planing-machine, the combination of an upper horizontally-disposed cutter-head, a feeding-in table thereunder, a horizontally-disposed lower cutter-head, inclined ways for supporting the feeding-in table with means for raising and lowering the table on the incline ways toward and from both cutter-heads simultaneously, an independent toe for the feeding-in table adjacent to the lower cutter-head, with means for permitting the adjustment of the toe on the table toward and from the lower cutter-head, substantially as described.
7. In a planing-machine, the combination of upper and lower horizontally-disposed rotary cutter-heads cutting in advance to reduce the stock to a uniform thickness, with a horizontally-disposed stationary-knife cutting device cutting thereafter, with a pulley in line with the lower cutter-head for rotating the same, and a clutch interposed between the pulley and the cutter-head, and means for longitudinally removing the cutter-head with its spindle and bearings, without disarranging the pulley, substantially as described.
8. In a planing-machine, the combination of a frame, a rotary cutter-head, a yoke in which the cutter-head is journaled slideable with relation to the frame, a bearing rigid with relation to the frame, with means for rotating the cutter-head journaled in the bearing, and a clutching device operatively interposed between said means and the cutter-head for allowing the longitudinal movement of the cutter-head yoke without disarranging the means for rotating the cutter-head, substantially as described.
9. In a planing-machine, the combination of a frame, a saddle adjustable thereon, a cutter-head yoke slideable longitudinally with relation to the saddle, a cutter-head journaled in the yoke, with a bearing on the saddle, a pulley for operating the cutter-head journaled in the bearing, with a clutching device operatively interposed between the pulley and the cutter-head, substantially as described.
10. In a planing-machine, the combination of a frame, with a saddle adjustable, a yoke slideable longitudinally of the saddle, a bearing at each end of the yoke with a cutter-head journaled in the bearings, a bearing on the saddle beyond the end of the cutter-head and in line with the bearings on the yoke, with a pulley for the cutter-head journaled in the bearing on the saddle, and a connection operatively interposed between the pulley and the cutter-head shaft for permitting the sliding of the cutter-head yoke without disarranging the pulley or its belt, substantially as described.
11. The combination, in a planing-machine, of a fixed knife set diagonally of the feed-rolls, and a continuous diagonal rotatable pressure agency over the knife, substantially as described.
12. In a planing-machine, the combination of upper and lower horizontally-disposed rotary cutter-heads cutting in advance to reduce the stock to a uniform thickness, with a horizontally-disposed stationary-knife cutting device comprising a stationary knife set diagonally of the feed-rolls cutting thereafter, with a diagonal pressure agency for the latter having substantially continuous rotatable pressure-faces, substantially as described.
13. In a planing-machine, the combination of a frame, a diagonal bar, sleeves taking thereabout having diagonal bore and journal-face extending longitudinally of the sleeve and diagonally to the shaft, with roll-sections taking over the sleeves, to make a substantially continuous transverse bearing on the stock, substantially as described.
14. In a planing-machine, the combination of a frame, a series of roll-sections, each roll-section having a bearing-face for the stock, with the bearing-faces projecting in parallel lines, with a diagonal bore within each section, and with the sections arranged diagonally of the frame and mounted upon a single support taking therethrough and forming a substantially continuous pressure agency, substantially as described.

15. In a planing-machine, the combination of a housing carrying a plurality of series of roll-sections, each having a bearing-face with the bearing-faces projecting in parallel lines, 5 with a diagonal bore in each section, and with the sections of each series arranged diagonally of the frame and mounted upon a single support taking therethrough and each series forming a substantially continuous pressure 10 agency, substantially as described.
16. In a planing-machine, the combination of a diagonal bar with sleeves having diagonal bore taking thereabout and secured fixedly with relation to the bar, with roll-sections 15 having bearings diagonal to the sleeve-bore, with their contacting faces with the stock in a common horizontal plane and their side faces arranged in parallel lines in advance of each other and forming a continuous pressure 20 agency, substantially as described.
17. In a planing-machine, the combination of a diagonal bar with sleeves having diagonal bore taking thereabout and secured fixedly with relation to the bar, with roll-sections 25 having bearings diagonal to the sleeve-bore, with their contacting faces with the stock in a common horizontal plane and their side faces arranged in parallel lines in advance of each other and forming a continuous pressure 30 agency, and boxes for each shaft, stationary with relation thereto, substantially as described.
18. In a planing-machine, the combination of a diagonal bar with sleeves having diagonal 35 bore taking thereabout and secured fixedly with relation to the bar, with roll-sections having bearings diagonal to the sleeve-bore, with their contacting faces with the stock in a common horizontal plane and their side faces 40 arranged in parallel lines in advance of each other and forming a continuous pressure agency, boxes for each shaft, stationary with relation thereto, a spring or similar means for yieldingly holding each box in normal position, substantially as described.
19. In a planing-machine, the combination 45 of a frame, a stationary cutting-knife extending transversely of the frame but diagonally thereto, a diagonally transversely extending bar in substantially the vertical plane of the cutting edge of the knife with a series of pressure-roll sections having parallel contact-faces for the stock extending at substantially 55 right angles to the frame and arranged to rotate about the shaft or rod with their contact-faces maintained in parallel lines and substantially continuous, substantially as described.
20. In a planing-machine, the combination 60 of a frame, a rotary cutter-head, a yoke in which the cutter-head is journaled slideable with relation to the frame, a bearing rigid with relation to the frame, with means for rotating the cutter-head journaled in the bearing, and a clutching device operatively interposed between said means and the cutter-head 65 for allowing the longitudinal movement of the

cutter-head yoke without disarranging the means for rotating the cutter-head, with pressure devices for holding the stock against the cutter-head, substantially as described.

21. In a planing-machine, the combination of a rotary side cutter-head and a stationary-knife cutting device arranged to each side of the stock passing through the machine, a slide 75 in which the stationary-knife cutting device is mounted, with means for the lateral adjustment of the slides and the rotary cutter-heads, with an arm swinging upwardly with relation to the slides and movable transversely with a side cutting agency, and means for rigidly securing the arm with relation thereto, and a pressure-bar extending longitudinally between the rotary cutter-head and stationary-knife cutting device at each side 85 of the stock, respectively, with means for adjusting the pressure-bar in the arm, substantially as described.

22. In a planing-machine, the combination of a rotary cutter-head and a stationary-knife cutting device mounted to each side of the stock passing through the machine, means for adjusting the rotary cutter-heads transversely of the machine, a slide for each of the stationary-knife cutting devices, with means 95 for transversely adjusting the slide, a swinging arm supporting an adjustable pressure-bar extending longitudinally between the cutters swinging away from the cutters to expose the same, with means for securing the free end of the arm to the slide to hold the pressure-bar in rigid position and move the same laterally with the slide, substantially as described.

23. In a planing-machine, the combination 105 of upper and lower horizontal rotary cutter-heads cutting in advance with a horizontally-disposed stationary-knife device cutting thereafter, with a vertically-disposed rotary cutter-head and a stationary-knife cutting 110 device for each edge of the stock, arranged to operate upon the stock in the order named, with a shaft or rod extending transversely of the machine and an arm or arms swinging therefrom and sliding thereon, a pressure-bar 115 slideable in the arm and adjustable up and down therein and located beyond the horizontal stationary-knife cutting devices between the vertically-disposed rotary cutter-heads and the vertically-disposed stationary-knife 120 cutting devices, respectively, with a slide for each of the vertically-disposed stationary-knife cutting devices, with means for rigidly securing the free ends of the swinging arms with relation thereto and permitting the lateral adjustment of the latter with the former, 125 substantially as described.

In testimony whereof I have signed my name hereto in the presence of two subscribing witnesses.

JOHN R. THOMAS.
